Patented June 20, 1922.

Inventor
Rudolph Frick

By Malow Fenwick Lawrence,
Attorney

UNITED STATES PATENT OFFICE.

RUDOLPH FRICK, OF BURLINGTON, IOWA.

AUTOMATIC MAIL-POUCH CATCHER.

1,420,874.

Specification of Letters Patent. Patented June 20, 1922.

Application filed September 7, 1920. Serial No. 408,556.

To all whom it may concern:

Be it known that I, RUDOLPH FRICK, citizen of the United States, residing at Burlington, in the county of Des Moines and 5 State of Iowa, have invented certain new and useful Improvements in Automatic Mail-Pouch Catchers; and I do hereby declare the following to be a full, clear, and exact description of the invention, such as 10 will enable others skilled in the art to which it appertains to make and use the same.

This invention relates to new and useful improvements in mail sack catchers and more particularly to a device of this character which is so arranged with respect to 15 the car to which it is attached that the sacks of mail which are caught thereby will be readily deposited upon a table upon the interior of the car.

20 The main object of the present invention is the provision of a railway mail catcher mounted for swinging movement within the top portion of a car and adapted to be disposed in an inclined position, whereby one 25 end of the device will be disposed in such a position that it will readily receive a mail sack or the like suspended alongside the railway track.

Another object of the present invention is 30 the provision of a mail sack catcher adapted to be movably disposed within a railway car and normally disposed in parallel relation with respect to the car and when it is desired to use the same, the device can be disposed at an angle to extend one end above 35 the roof of the car for receiving a mail sack or the like suspended along the track.

A further object of the present invention is the provision of a mail sack catcher of 40 the above character provided with a plurality of retarding members to thus eliminate the jar of the mail sack when being thrown into the car so that any of the articles contained within the bag will not be 45 come broken, regardless of how fragile they may be.

A further object of the invention is the provision of a cagelike device mounted within 50 a railway car and adapted to have one end projected above the car for engaging a mail sack suspended alongside the track, said cage being provided with a plurality of retarding members against which the mail sack is thrown to retard the speed of the 55 sack upon entering the car. It will be noted that this device will readily receive the mail

sack without injuring the contents thereof, regardless of the speed of the train.

With the above and other objects in view, the invention consists in the novel features 60 of construction, the combination and arrangement of parts hereinafter more fully set forth, pointed out in the claims and shown in the accompanying drawings, in which—

65 Figure 1 is a side elevation of a railway car, showing the application of my improved mail sack catcher,

Figure 2 is an end elevation, showing the position of the catcher with respect to the 70 suspension means alongside the track,

Figure 3 is a side elevation of the cage which receives the mail sacks, and

Figure 4 is a front end elevation of the same.

75 Referring more particularly to the drawings, it will be noted that I have shown for the purpose of illustration a diagrammatic view of a railway car, generally indicated by the numeral 1, showing my improved mail 80 catcher attached thereto. In the present instance, my improved catcher is mounted within a suitable opening formed in the top of the car and when not in use will be disposed parallel with the body of the car 85 and when desired for use can be swung to an angular position so that one end of the catcher projects above the roof of the car.

In the present instance, I have shown my 90 improved catcher as mounted within an opening in the car 1, but I do not wish to limit myself to this particular construction or mounting of the catcher upon the car, as the same can be readily used in various positions with respect to the car. The catcher, 95 in itself, includes bowed base members 2, connected at their ends by means of the transverse members 3 and in order to provide a body or cagelike device, the U-shaped members 4 are provided, the ends of which 100 are secured in any desired manner to the bowed portions 2.

Attached to the intermediate portion of the sides of the members 4 are the longitudinal strips 5, the ends of which are secured 105 to the strips 6 which form the top and end strips of the frame. These strips 6 are preferably U-shaped in form, the forward ends of the same being disposed at an angle, as shown at 7, while the rear ends are perpendicular to the strips 2 and 5 and parallel 110 with the strips 4. The intermediate por-

tions of the members 6 constitute the top portion of the frame with the exception of the inclined portions 8 arranged upon opposite sides of the center of the frame to 5 provide an inclined portion at each end of the cover or roof of the catcher.

If found necessary, a suitable covering may be arranged over the top of the cage, but in the present instance the use of such 10 a cover has not been illustrated. The car 1 is provided upon each side of the opening therein for the purpose of receiving the catcher with standards 9 having suitable bearings at their upper ends adapted to 15 receive a transverse rod 10, the ends of which are secured to the center one of the U-shaped members 4 for the purpose of mounting the catcher for swinging movement within the opening in the car, whereby one end of the 20 catcher may be disposed above the roof of the car, as illustrated in Figure 1, for the purpose of receiving the mail sacks which are suspended alongside the track.

In Figure 2, I have illustrated the manner 25 in which the mail sacks may be suspended alongside the track and in this construction it includes a standard 11, having a swinging supporting bar 12 on its upper end provided with a suspension member 13. This suspension member 13 may be of wood or other 30 material, whereby when the sack is caught within the front end of the catcher, this suspension member will be broken for the purpose of releasing the sack supported 35 thereby. While this particular means is shown and described for releasing the sack from the member 12, it will be understood that any suitable releasing mechanism can be used if desired. It is obvious that should 40 a mail sack be received within the forward end of the catcher while the train is going at a high rate of speed, the sack would be thrown into the car with great force, should there be no means for retarding the movement 45 of the same, as it passes through the catcher and into the car. In order to retard the movement of the sack when received into the catcher, I provide a plurality of S-shaped retarding members, generally indicated by 50 the numeral 14. These members 14 are secured at their upper ends to the bowed supporting member 15, the ends of which are attached to the angular portions 8 of the members 6 to support the member 55 15 in its proper position. It will be noted that the members 14 are supported in such a manner that the lower curvature of the same will be engaged by the mail sack as it enters the cage and as these retarding members 14 60 are yieldable in construction, it will permit the mail sack to pass beyond each of the retarders to the rear end of the cage, where it will drop downwardly into the interior of the car. As the sack is received into the

forward end of the catcher and passes rearwardly, the members 14 will retard its movement so that when it reaches the rear end of the catcher and is deposited within the car, it will be deposited within the car with considerable less force than it would have 70 been were it not for the retarding members 14.

It is preferred, upon receiving the mail sacks into the car 1, to have them deposited upon a suitable table 16, arranged in position 75 within the car beneath the inner end of the catcher so that the mail sacks can be readily deposited upon this table when received within the car.

While I have shown and described particular means for mounting this catcher within an opening in the roof of the car 1, it will be understood that I do not wish to limit myself to this particular mounting or the position of the catcher within the car. In order 85 to retain the U-shaped members 4 and 6 in their proper relative positions with respect to the longitudinal members 2 and 5, I provide a plurality of brace wires 17 which are attached to the side portions 4 of the U- 90 shaped members and the end portions of the member 6.

What I claim is:

1. A device of the class described including in combination with a car body having 95 an opening in the top thereof, of a movable cage member normally supported within the car and adapted to be disposed in an inclined position with one end projecting through the opening to receive a suspended 100 mail sack for depositing the same within the car and a plurality of S-shaped yieldable retarding members, each having one of their ends secured to the cage and their free ends disposed in the pathway of the mail 105 sack as it passes through the cage to retard the movement of the same.

2. A device of the class described including in combination with a car body having 110 an opening in the top thereof, of a movable cage member normally supported within the car and adapted to be disposed in an inclined position with one end projecting through the opening to receive a suspended 115 mail sack for depositing the same within the car, a series of retarding members arranged within the cage in longitudinal alignment, each series comprising a plurality of S-shaped spring members arranged 120 in transverse alignment with respect to the cage, each of said spring members having one of their ends secured to the cage and their free ends disposed in the pathway of the mail sack as it passes through the cage 125 to retard the movement of the same.

In testimony whereof I affix my signature.

RUDOLPH FRICK.
